CLAIM

The ornamental design for an aerial work platform vehicle, as shown and described.

DESCRIPTION

FIG. 1 is a perspective view of an aerial work platform vehicle showing our new design;

FIG. 2 is another perspective view thereof;

FIG. 3 is a front view thereof;

FIG. 4 is a rear view thereof;

FIG. 5 is a left side view thereof;

FIG. 6 is an enlarged left side view thereof;

FIG. 7 is a right side view thereof;

FIG. 8 is an enlarged right side view thereof;

FIG. 9 is a top view thereof; and,

FIG. 10 is a perspective view of the aerial work platform vehicle in an alternate condition of use.

1 Claim, 10 Drawing Sheets
